UNITED STATES PATENT OFFICE.

FELICE GILARDINI, OF TURIN, ITALY.

BELT.

1,309,066.

Specification of Letters Patent.

Patented July 8, 1919.

Application filed April 6, 1918. Serial No. 227,051.

To all whom it may concern:

Be it known that I, FELICE GILARDINI, tanner, a subject of the King of Italy, residing at and whose post-office address is 5

5 Via Giannone, Turin, in the Kingdom of Italy, have invented certain new and useful Improvements in Belts; and I do hereby declare the following to be a full, clear, and exact description of the invention, such as 10 will enable others skilled in the art to which it appertains to make and use the same, reference being had to the accompanying drawings, and to letters or figures of reference marked thereon, which form a part of this 15 specification.

The invention relates to belts for the transmission of power in machinery and the like and the object of the invention is to produce a belt of this character having the 20 advantages of not being liable to stretch during use and possessing a greater tensile strength than belts heretofore known. Said advantages are obtained by a process which consists chiefly in tanning the hides or skins 25 only in successive sections separated by narrow parts, which are unprepared but highly compressed, the tanning and compression operation being effected while the hides or skins are kept under the utmost tension. It 30 would also be possible to obtain a belt having the above named qualities by superficially tanning the parts extending between the tanned ones with fats or the like, in order that the belt may be used advantageously 35 even in wet places. For the same purpose it would be advantageous to soak the skin, before stretching it, in a tan liquor, preferably constituted by a mineral solution, which penetrates in a very small quantity the flesh 40. as well as the hair side of the skin.

This belt is illustrated, by way of example and diagrammatically in the annexed drawing.

Figures 1 and 2 are respectively a plan 45 view and a section of the belt, in which the tanned parts are circular; Figs. 3 and 4 are similar views of a belt of the present type, in which the tanned parts are of rectangular form;—Figs. 5 and 6 show belts of the 50 present type put on a pulley in order to show their advantages.

The rectangular piece of the skin called the "butt" is used for this belt, as it is the general rule in the processes already known 55 when belts of good quality are to be pro-

duced. Said butt is obtained in the usual manner by cutting a rectangular piece in the best and central part of the raw skin.

The butt, either in one piece or cut, as it is preferable, in two, three or more lengths is 60 placed in a stretching device, drawn to the utmost tension and kept in this condition. Said device may be constituted for instance by a rod, on which are fitted two vises, one of which is stationary while the other is 65 movable, said vises being connected with the two hooks of an ordinary stretching apparatus. By causing the screw acting on the hook connected with the movable vise to rotate, this latter is moved from the stationary 70 vise, drawing out the hide or skin until the utmost elongation is obtained. The bolts that fasten the movable vise on the rod are then screwed in, thus preventing the hide or skin from shrinking when the rod with 75 the two vises, between which the hide is stretched, is removed from the stretching apparatus. On both sides of the butt, thus maintained in a stretched condition, two "grates" with corresponding openings are 80 then applied.

Said "grates" must be disposed one on the hair and the other on the flesh side of the butt, and will be secured by suitable means in order to highly compress all the 85 parts of the skin comprised between the corresponding openings of the two grates. The frame, constituted by the skin drawn between the grates and the vises, is afterward removed and the tannage carried out 90 in any of the well known processes. I may, for instance, put a series of frames thus formed in pits, or to hasten the completion of the operation, in series of drums by placing them in layers or, still better, on a revolving support, the rectangular arms of 95 which turning in the liquor, are constituted by the said frames.

The tannage of said butts may be carried on more rapidly and therefore more advantageously in the apparatus forming the subject matter of my application filed April 6, 1918, Serial Number 227,050. By using said apparatus, an instantaneous tanning is effected, the tanned parts having any desired form. (for instance, square, rectangular, circular, triangular, etc.) according to the form of the cells of the machine plates, which must be reduced to the number of two, one plate being placed above the other. 105 110

The skin must be maintained drawn between the two vises, but of course the special "grates" will not be required in this case.

When the tanning operation has been effected, according to any desired process, the washing with running water will be carried on, the hides being still kept in the stretched condition; thereupon the gradual drying operation will take place, further the dressing 10 and then the treatment with grease, using the usual substances (for instance, oils, dégras, tallow and the like) either by soaking or preferably by stuffing or in any other known way. The hides are then slowly 15 dried until quite dry and finally taken off the frame and hammered, or, preferably, rolled. The manufacture of the belts obtained from this leather will then take place in the usual way, cutting the butts in more 20 or less wide strips according to the desired thickness and size of the belts and effecting the several following well known operations. The belts obtained by this process are therefore constituted by tanned parts 25 separated by unprepared but strongly compressed parts. Now it is well known that the unprepared but strongly compressed hide or skin acquires a high resistance, equal to 7 and 8 K. per mm^2 of breaking 30 load, while the tanned skin has a maximum tensile strength of 3 to $3\frac{1}{2}$ K. per mm^2 and undergoes a remarkable elongation. As the tanned parts in this belt are separated by unprepared ones, the belt will not be 35 stretched in a noticeable degree, owing to the stiffness of the unprepared parts, while the pliancy of the tanned parts will allow the fitting of the belt on the pulleys, as it appears clearly from Figs. 5 and 6; moreover the belts have a greater tensile strength 40 than the belts known heretofore.

This belt shows moreover the advantage of a proper grip of the pulley produced by the tanned parts which are of a greater

thickness than the unprepared ones (see 45 Figs. 2, 3, 5, 6); its working may be compared to a Gall's chain or similar chain having numerous links joined side by side, the stiff unprepared parts would correspond to the links of the chain and the supple parts 50 to the joints. The roughness of the belt surface that lies on and adheres to the pulley only with the tanned parts produces the proper grip aforesaid.

Finally it will be observed that a belt of 55 this type could be obtained by causing the openings of the two grates to be displaced more or less with respect to each other in order to obtain always on each side of the hide or skin tanned parts separated by stiff 60 unprepared parts, but in such a way that a tanned part on one side corresponds more or less with an unprepared part on the other side.

Hides or skins tanned according to this 65 process may be used for any other purpose beyond that here mentioned for the manufacture of belts.

What I claim is:

1. A one ply belt having tanned portions 70 separated by untanned portions.
2. A single ply leather belt having tanned and untanned portions.
3. A single ply leather belt having tanned portions, and compressed untanned portions 75 separating the tanned portions.
4. A belt having shaped, pliable, tanned thick portions surrounded by untanned portions thinner than the tanned portions.
5. A belt for the transmission of motion 80 in machinery having shaped pliable tanned portions, separated by compressed, stiff, highly resistant and superficially treated portions thinner than the tanned portions.

In testimony that I claim the foregoing as 85 my invention, I have signed my name.

FELICE GILARDINI.
